COMBINED STORAGE LOCKER AND PORTABLE BASKETBALL GOAL

Robert L. Hulsebus, 432 N. Main St., Saluda, S.C.

Filed Dec. 29, 1959, Ser. No. 58,843

Term of patent 14 years

(Cl. D34—5)

Figure 1 is a perspective view of a combined storage locker and portable basketball goal showing my new design, the two sides not shown being substantially the same as the plain side shown;

Figure 2 is a reduced front elevational view thereof;

Figure 3 is a top plan view thereof;

Figure 4 is a front elevational view of a combined storage locker and portable basketball goal showing my new design wherein the backboards are curved rather than rectangular; and

Figure 5 is a top plan view thereof.

The essential feature of my design resides in the com-

bination of a four sided upright storage locker carrying a corresponding number of basketball goals and backboards projecting from the upper end thereof substantially as shown.

I claim:

The ornamental design for a combined storage locker and portable basketball goal, as shown and described.
